COKING OF OIL

Jacque C. Morrell, Chicago, Ill., assignor to Universal Oil Products Company, Chicago, Ill., a corporation of South Dakota

Application December 28, 1931, Serial No. 583,598

1 Claim. (Cl. 202—29)

This invention relates to an improvement in the process for facilitating the cleaning of reaction or coking chambers and apparatus relating thereto. More particularly the invention is adapted to the type of cracking process in which the oil is usually passed through a suitable heating or cracking coil and thence into an enlarged reaction chamber in which substantial quantities of coke are formed. In its broader aspects, however, the invention is not limited to a cracking operation but may relate to any form of coking operation.

By means of the present invention, coke removal is greatly facilitated. This is important in connection with the manufacture of high anti-knock gasoline in which process a greater percentage of coke may be formed as well as coke of a much harder nature, making it more difficult to remove from the reaction chamber.

To this end, I provide a plurality of spaced members which preferably take the form of a lattice work and are capable of being charred so that they will easily break up during the removal of the coke. This lattice work, in effect, forms within the body or mass of coke what may be designated weak breakage planes along which the coke will break into smaller particles or bodies during the coke removing operation. If desired, the coke removal may be further facilitated by means of a cable-pulling operation of well known type.

It may be here stated that the lattice work referred to preferably is collapsible so that it can be more readily inserted into the reaction chamber. This lattice work is preferably made of wooden strips spaced apart as shown in the drawings, or may be of some other material that will char under the heat in the coking chamber and thus be sufficiently weakened to readily break when it is attempted to remove the coke from the chambers.

The attached diagrammatic drawings illustrate a reaction chamber, such as that used in the conversion of hydrocarbon oils, to which the principles of the present invention have been applied.

Fig. 1 is a plan view of the chamber taken along the section indicated by line 1—1 in Fig. 2. 50 Fig. 2 is a side elevation of the same chamber, shown partially in cross-section.

Fig. 3 is an elevation of the same chamber, shown partially in a section taken along line 3—3, in Fig. 2.

55 Fig. 4 is a view in vertical section of the lattice-

work, assembled in compressed form ready to be inserted in the chamber.

Fig. 5 is a fragmentary vertical sectional view showing the lower portion of the reaction chamber provided with a slightly modified form of 60 lattice-work.

Fig. 6 is a sectional plan view of the chamber taken along line 6—6, in Figure 5.

Referring particularly to Figures 1, 2, 3 and 4 of the drawings: The shell of the chamber is indicated at 1. The upper manway opening is indicated at 2 and the lower manway opening at 3.

Lattice-work structures 4 of wood or other easily charred material, extend across the chamber and preferably comprise members 5 and 6 joined substantially at right angles to each other, extending diagonally throughout the total height or any desired portion of the chamber. Structure 4 is

preferably so constructed that it may be compressed, as illustrated in Fig. 4, for insertion 75 through the manway openings so that it may be assembled outside the chamber. These lattice-work structures 4 may be expanded after their

insertion into the chamber and may be suspended therein by means of hooks, as illustrated at 7, or 80 by any other well known means. Other members of wood or other easily charred material, indicated in the drawings at 8, may be inserted in the openings provided between the members of

the lattice-work structure 4 and may rest upon 85 the intersecting members 5 and 6 of this structure. The members 8 are preferably placed sub-

stantially at right angles to the planes occupied by the structures 4, thus dividing the space with- 90 in the chamber in which carbonaceous material is to be deposited into a series of both horizontal and vertical planes defined, prior to the deposition

of the coke or carbonaceous material, by the members 5, 6 and 8 of the wooden structure and 95 subsequent to such deposition by vanes of charred wood or charcoal, formed by the effect of heat in the deposited material upon said members 5, 6 and 8. This charring of the lattice-work struc-

ture forms planes of weakness throughout the carbonaceous deposit which facilitate breakage 100 and removal of said deposit from the chamber.

Referring now more especially to Figures 5 and 6 which illustrate a method of placing a lattice-work structure in a reaction chamber in conjunc-

tion with a cable suspended within the chamber 105 to assist in the removal of coke or carbonaceous material; the wall of the chamber is indicated at 1 and the lower manway opening at 3. Lugs 9, attached to the side walls of the chamber at in-

tervals around its inner circumference and at in- 110

tervals in the vertical height of the chamber, support wires 10 suspended radially across the inner-diameter of the chamber. Wires 10 in turn support a cable 11 which, as here illustrated, is wound spirally upon each of the successive planes defined by the series of radial wires 10. The lower end of the cable 11 is anchored to the lower manway cover 12 in any well known manner as indicated at 13. After coke has been deposited within the chamber, in any known manner as by distillation in the chamber, at a temperature of 900° F. or higher, of hot oil from a heating coil, or otherwise, manway cover 12 may be loosened and removed from the chamber, leaving the lower end 10 of cable 11 accessible so that it may be pulled, by means of a winch or tractor or other suitable means, not shown, to disrupt the carbonaceous mass in which the cable is embedded, permitting its removal from the chamber. This method is 20 well known and widely used. The novelty of the method illustrated in Figures 5 and 6 comprises providing means for assisting disruption of the carbonaceous mass in combination with the use of a cable, said additional means being embodied 25 by the provision of the present invention and consisting of a honeycomb or lattice-work structure of wood or other charable members supported upon the cable. The charable members are indicated at 14 and preferably comprise both 30 vertical members 15 and substantially horizontal members 16 and 17 so that when these members are charred by the heat of the carbonaceous mass

in which they are embedded intersecting planes of weakened structure are created which extend both vertically and horizontally throughout said carbonaceous mass. It will be apparent that upon pulling cable 11 the tendency of the coke or carbonaceous material will be to break along the planes defined by the vanes of charred wood or other material comprising the lattice-work structure so that relatively large cubes or lumps of coke will be broken away from the carbonaceous mass as the cable is pulled and a relatively small percentage of fine particles will result.

It will be understood that the types of structure shown in the drawings are only two of the many forms which may be employed within the scope 90 of the present invention, these particular structures being shown only for the purpose of clearly illustrating the features and the operability of the invention.

I claim as my invention:

In the coking of oil in enlarged chambers wherein the oil is subjected to a coking temperature and a substantial body of coke deposited from the oil in the chamber, the method of facilitating the removal of the body of coke from the 100 chamber which comprises positioning in the chamber in the form of a lattice-work a plurality of spaced rigid members capable of being charred by the heat of the oil whereby the body of coke will break along lines of cleavage furnished by the 105 charred members.
